UNITED STATES PATENT OFFICE.

GEORGE R. MEYERCORD, OF CHICAGO, ILLINOIS.

METHOD OF PRODUCING TRANSLUCENT PANELS.

1,080,990.

Specification of Letters Patent.

Patented Dec. 9, 1913.

Application filed August 17, 1910. Serial No. 577,760.

To all whom it may concern:

Be it known that I, GEORGE R. MEYERCORD, a citizen of the United States, residing at Chicago, county of Cook, State of Illinois, have invented a certain new and useful Improvement in Methods of Producing Translucent Panels, and declare the following to be a full, clear, and exact description of the same, such as will enable others skilled in the art to which it pertains to make and use the same, reference being had to the accompanying drawings, which form a part of this specification.

My invention has for its object to produce a simple and efficient method of making flexible, translucent decorative panels or panels carrying inscriptions or legends; such panels being adapted to be used instead of glass.

20 In accordance with my invention I make use of a fine mesh wire screen or other perforated, flexible sheet to form the body of the panel, mount a colored translucent decalcomania film thereon, and cover the whole with a translucent material which enters into the interstices in the screen.

25 In the accompanying drawing I have illustrated a panel under the different conditions which may be encountered during the process of making the same: Figure 1 being a cross section on an exaggerated scale of a portion of a wire screen after a decalcomania film has been pressed thereon; Fig. 2 being a view similar to Fig. 1, showing a defect which often occurs upon the removal of the pressure from the film; Fig. 3 being a view similar to Figs. 1 and 2 illustrating the panel shown in Fig. 2 after the application of the adhesive coating; and Fig. 4 being a side elevation of a fragment of the completed panel on an enlarged scale.

30 My invention can best be described by referring to the drawing.

40 I take an ordinary fine mesh wire screen, indicated at α in the drawing and mount upon one side thereof a colored, translucent, decalcomania film indicated at b . When the film is mounted, the transfer sheet is placed between the screen and a soft pad which will yield under pressure and enter the interstices of the screen, carrying portions of the film with it and producing in the film numerous cup-like sections which extend into the spaces between the wires, 45 the transfer sheet being first made wet by dipping it in water, pouring water over it, or in any other usual manner. In Fig. 1 I have illustrated three wires a , a' and a'' and two cup-like film sections b and b' which extend to the spaces between the wires. 50 The member b , it will be seen, follows the curvature of the wires and therefore adheres closely thereto. Another similar section, which may be the section b' , for some reason or other may not be pressed as snugly between the wires as the section b . Therefore, when the pressure upon the film is removed, and all the stretched portions of the film are under a tension tending to restore them to their normal flat condition, 55 the section b' , which is insecurely held, will flatten out as indicated at b^{10} in Fig. 2. It is evident that where some of the cup-like portions retain their shape while others flatten out, an uneven irregular surface is 60 produced which distorts the decoration and detracts greatly from the appearance of the panel. Furthermore if the panel were used in this form the film would soon dry and crack and even before this happened it 65 might be injured by coming in contact with some hard object. I have found that the film may be protected against injury through contact with hard objects and prevented from cracking by covering the panel 70 with some translucent adhesive substance such as varnish or shellac, the adhesive substance also filling the interstices in the screen about the film. The varnish or shellac may be applied in various ways but I 75 have found that a peculiar advantage results from dipping the screen into the varnish or shellac after the film has been applied and then permitting the excess of varnish or shellac to drip from the panel. 80 When the panel is dipped the varnish enters 85 into the spaces between the wires and comes in contact with both sides of the film. When the panel is lifted from the bath the excess of varnish or shellac begins to run 90 down the same and tends to draw out of the interstices the small bodies which have collected therein. Now there will be considerable body of varnish or shellac between the wires a' and a'' and engage with the film 95 section b^{10} . The film at this point, having previously been stretched, and also because it is naturally thin and flexible, yields to the pull upon the adhesive body back of it and is drawn inwardly into substantially its 100 original cup-like shape as indicated at b' in Fig. 1; the varnish or shellac being suffi-

ciently viscous to transmit the pull to the film. After the film has been drawn in far enough to make its resistance greater than the tensile strength of the body of varnish or shellac behind the same, further movement thereof will cease and the varnish or shellac will begin to set and harden so as to hold the film in the position into which it has been drawn. The condition of the parts 5 after the excess of varnish or shellac has been allowed to run off of the panel is illustrated in Fig. 3, there being a layer of shellac or varnish C on the front side of the film and the second layer C' extending along 10 the rear side and filling the spaces between the wires.

A panel made in accordance with the present invention will be strong, light and flexible; it will have the appearance of pebbled 20 glass under transmitted light; and the translucent colored subject will appear in a beautiful glow, the light being uniformly distributed by reason of the uniformity in the surface of the film. Furthermore the panel 25 may be washed in the same way as glass so that it may be kept bright and clean.

What I claim is:

1. The process of making a decorated translucent panel which consists in pressing 30 a decalcomania film in a dampened condition upon a wire screen so as to cause the

film to stretch into cup-like sections extending into the interstices of the screen, and then applying an excess of varnish to the screen before the film dries and allowing the 35 surplus of varnish to run off.

2. The process of making a decorated translucent panel which consists in pressing a decalcomania film in a dampened condition upon a wire screen so as to cause the film to 40 stretch into cup-like sections extending into the interstices of the screen, and then dipping the screen in varnish or shellac and holding it so as to permit the excess of varnish or shellac to run off. 45

3. The process of making a decorated translucent panel which consists in pressing a decalcomania film upon a wire screen so as to cause the film to stretch into cup-like sections extending between the wires of the 50 screen, and then dipping the screen in varnish or shellac before the film becomes hard and dry and permitting the excess of varnish or shellac to run off so as to restore the cup-like configurations of any sections 55 which may have become flattened.

In testimony whereof, I sign this specification in the presence of two witnesses.

GEORGE R. MEYERCORD.
